W. GREENFIELD

ELECTRIC GAS LIGHTER

Filed Feb. 12, 1924

His Attorney

UNITED STATES PATENT OFFICE.

WILLIAM GREENFIELD, OF PHILADELPHIA, PENNSYLVANIA.

ELECTRIC GAS LIGHTER.

Application filed February 12, 1924. Serial No. 692,216.

To all whom it may concern:

Be it known that I, WILLIAM GREENFIELD, a citizen of Hungary (having declared his intention of becoming a citizen of the United States), residing at Philadelphia, in the county of Philadelphia and State of Pennsylvania, have invented certain new and useful Improvements in Electric Gas Lighters, of which the following is a specification.

10 My invention relates to electric gas lighters and its objects are to provide a gas lighter of simple and durable construction which will light the gas in a gas range by rubbing an electrode over the gas burner to produce electric sparks, and to provide a handle for the electrode which will protect it against contact with other parts of the range when not in use.

These objects, and other advantageous ends which will be described hereinafter, I attain in the following manner, reference being had to the accompanying drawings in which

Figure 1 is a central section through a handle constructed in accordance with my invention,

Figure 2 a section on line 2—2 of Figure 1, and

Figure 3 a diagrammatic view of the electrical connections to the handle.

Referring to the drawings, 1 indicates a gas range, 2 the burners and 3 the pipe connecting the burners and leading to the ground 4. My improved handle 5 houses an electrode which is connected by a wire 6 to an electric lamp 7 which is connected at 8 to one pole of the house current. The construction of the handle includes a casing 9 of insulating material, preferably wood; a terminal plate 10 having an electrode 11 secured thereto; a cap 12 of insulating material screwed onto the casing and securing the terminal plate therebetween, and a guard sleeve 13, preferably of porcelain, slidable on the electrode and within the cap. The guard sleeve normally extends over an end 14 of the electrode and is provided with a shoulder 15 which abuts the inside of the cap to prevent outward movement of the sleeve. A spring 16 is interposed between sleeve 13 and terminal plate 10 to keep the sleeve over end 14 of the electrode. The terminal plate is provided with fastening holes 17 and 18 through which passes the

conduit wire 6 which is electrically connected to the plate by a screw 19. It is readily seen that by passing the conduit wire 6 through holes 17 and 18 as shown in Figures 1 and 2, pulling or jerking the wire will not disrupt its electrical connection with the terminal plate.

In producing electric sparks to light the gas, the current passes from the connection 8 of one pole of the house current through lamp 7, conduit 6, electrode 11, burner 2, 65 gas pipe 3 to the ground 4. The ground, which is usually connected to the other pole of the house current, conducts the current to the other pole to complete the circuit.

To light the gas burner, guard sleeve 13 70 is brought into contact with the burner and pressed inward until the end 14 of the electrode engages the burner. The electrode is then rubbed over the burner and the gas turned on. Lamp 7 prevents the fuse from 75 blowing out when the circuit is completed and thereby eliminates high resistance transformers.

By connecting and making a gas lighter as above described the electrode is protected 80 against contact with the gas range when not in use, and the fuses, for the house current, will not blow out.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. An electric gas lighter including a handle; an electrode having one end secured in and the other end extending out of the handle; a conduit wire electrically connected with the electrode and within the handle, and a guard sleeve slidable on the free end of the electrode.

2. An electric gas lighter including a handle; an electrode having one end secured in and the other end extending out of the handle; a conduit wire electrically connected to the electrode; a guard sleeve slidable on the free end of the electrode, and resilient

means between the handle and the sleeve for keeping the sleeve over the end of the electrode.

3. An electric gas lighter including a handle; an electrode having one end secured in and the other end extending out of the handle; a conduit wire electrically connected to the electrode; a guard sleeve slidable on the free end of the electrode, and a coiled 10 spring around the electrode between the handle and the sleeve for keeping the sleeve over the end of the electrode.

4. An electric gas lighter including a casing; an electrode having one end secured 15 in the casing; a cap secured to the handle and enclosing part of the electrode; a conduit wire passing through the casing and electrically connected to the electrode; a guard sleeve slidable on the electrode and in 20 the cap, and resilient means for keeping the guard sleeve over the end of the electrode.
5. An electric gas lighter including a casing; a terminal plate; an electrode secured to the plate; a cap securing the plate 25 to the casing and enclosing part of the electrode; a guard sleeve slidable on the elec-

trode and in the cap, and resilient means for keeping the guard sleeve over the end of the electrode.

6. An electric gas lighter including a 30 casing; a terminal plate having fastening holes; an electrode secured to the plate; a conduit wire passing through the holes and electrically connected to the plate; a cap securing the plate to the handle and enclosing 35 part of the electrode; a guard sleeve slidable on the electrode and in the cap, and resilient means for keeping the guard sleeve over the end of the electrode.

7. An electric gas lighter including a 40 casing; a terminal plate; a cap securing the terminal plate to the casing; an electrode secured to the plate and extending out of the cap; a guard sleeve slidable on the electrode and in the cap; a shoulder on the 45 sleeve engaging the cap for preventing outward movement, and resilient means for keeping the sleeve over the end of the electrode.

In testimony whereof I have signed my 50 name to this specification.

WILLIAM GREENFIELD.
